G. E. BRENT

CASING FOR A CANDY MACHINE

Filed May 29, 1922

INVENTOR:

George E. Brent,
by A. T. Halsell, his Attorney.

Patented Jan. 12, 1926.

Des. 69,199

UNITED STATES PATENT OFFICE.

GEORGE E. BRENT, OF NASHVILLE, TENNESSEE.

DESIGN FOR A CASING FOR A CANDY MACHINE.

Application filed May 29, 1922. Serial No. 2,457. Term of patent 14 years.

To all whom it may concern:

Be it known that I, GEORGE E. BRENT, a citizen of the United States, residing at Nashville, in the county of Davidson and State of Tennessee, have invented a new, original, and ornamental Design for a Casing for a Candy Machine, of which the following is a specification, reference being had to the accompanying drawing, forming part thereof, in which the figure shows a side elevation of my new, original, and ornamental design.

I claim:

The ornamental design for a casing for a candy machine, substantially as shown.

GEORGE E. BRENT.
